(57) **CLAIM**

The ornamental design for a microwave oven pedestal, as shown and described.

DESCRIPTION

FIG. 1 is a bottom perspective view of a microwave oven pedestal showing the new design;

FIG. 2 is a bottom plan view thereof;

FIG. 3 is a top perspective view thereof;

FIG. 4 is a top plan view thereof;

FIG. 5 is a side elevational view thereof, the opposite side elevational view being the same as FIG. 5;

FIG. 6 is another side view thereof, the opposite side elevational view being the same as FIG. 6; and,

FIG. 7 is a bottom perspective view of a second embodiment of the microwave oven pedestal, the top plan view and the side elevational views being the same as in the first embodiment.
